UNITED STATES PATENT OFFICE.

BERNARD M. KRELL, OF NEW YORK, N. Y.

BINDER.

Application filed August 10, 1922. Serial No. 580,916.

To all whom it may concern:

Be it known that I, BERNARD M. KRELL, a citizen of the United States, residing in New York, N. Y., in the county of New 5 York and State of New York, have invented certain new and useful Improvements in Binders, of which the following is a specification.

This invention relates to binders for sewing machines or devices for applying edging or collarettes to the edge of fabrics though it is noted that the invention is in some respects not limited to binders nor even to sewing devices.

10 One object of the invention is to provide a device of this kind in which the upper and lower elements of the binder receive the upper and lower layers of the edging and are separable for the easy insertion of the 15 body fabric.

Another object of the invention is to provide an apparatus or device of this kind in which said upper element is attached to the presser foot of the sewing machine for 20 automatically separating said elements as the foot is raised.

Another object of the invention is to provide in an apparatus or device of this kind efficient guide means for guiding the edging 25 to the binder.

Other objects of the invention are to improve generally the simplicity and efficiency of such devices and to provide a device or apparatus of this kind which is durable, 30 economical to manufacture and operate and which will not get out of order.

The inventive features for the accomplishment of these and other objects are embodied in an improved binder which, briefly stated, 35 comprises in combination with the presser foot, an upper binder element secured to the foot, a fixed lower binder element under the upper element; superposed opposed guide channels for discharging into said channel 40 elements and curving rearwardly and laterally toward the receiving end, and a forwardly opening channel shaped yoke portion joining said guide channels at the receiving end and terminating short of the 45 curved portion.

50 Other objects of the invention will appear

as the description proceeds; and while herein details of the invention are described, the invention is not limited to these, since many and various changes may be made 55 without departing from the scope of the invention as claimed.

In the accompanying drawing, showing by way of example, one of many possible embodiments of the invention—

Fig. 1 is a plan of the binder and associated presser foot;

Fig. 2 is a side elevation of the binder and foot;

Figs. 3, 4 and 6 are vertical sectional views 65 respectively taken on the lines 3—3, 4—4 and 5—5 of Fig. 1, looking in the direction of the arrows of said lines; and

Fig. 6 is a fragmental perspective view 70 of the body fabric and edging.

My improved binder is intended for use with sewing machines for attaching, to body fabrics 10, (Fig. 6), collarettes or edging comprising upper and lower layers 12 and 13 secured together by overseaming at 75 the outer edge 14 and having inwardly turned creased inner edges 15 and 16. The binder itself is used in combination with the presser foot 17 (Fig. 1) of a sewing machine (not shown) and is in part carried by 80 a bracket plate 18 for attachment to the bed of the machine and provided with an upstanding flange forming an end guide face 19.

The upper layer 12 is guided in part by a 85 sheet metal channel shaped upper binder element 20 disposed longitudinal to the path of feed and receiving the inner edge 15 of said upper layer and closed at the outer side 21 and formed with a narrow 90 lower member 22 downwardly inclined toward its edge with an inclination very flat at the rear end and gradually steeper at the front end. The wide upper member 24 forms a part of or is secured to the forward 95 part of the lower face of the inside part of the foot 17 and is movable up and down therewith to permit the insertion of the body fabric 10 between said creased edges 15 and 16 and has its edge portion downwardly 100 inclined and disposed close to said face 19 and is provided with a rearwardly extended

reduced portion 25 between said face and the foot. The receiving end of the edge 21 is slit and the forward ends 26 of the members diverged to aid in the insertion of the 5 upper layer.

A channel shaped sheet-metal lower binder element 30 (Fig. 3) closed at the outer side 31 and receiving the inner edge of said lower layer is disposed under the upper 10 element 20 approximately symmetrical therewith relative to the plane of the body fabric 10 and is formed with a narrow upwardly and inwardly inclined upper member 32 of forwardly increasing inclination, between 15 which and said narrow lower element 22 of the upper member the body fabric is secured. The lower element also comprises a wide inwardly and upwardly inclined lower member 35 secured to said guide face 20 19.

Integral with said lower element 30 is a guide 36 (Fig. 1) extending rearwardly from said elements and provided with a rearwardly and laterally curved portion 37 25 (Figs. 1 and 4) merging into a substantially straight receiving portion 38. Said guide 36 is formed with lower and upper guide channels 40 and 41 for guiding said layers into said upper and lower elements respectively, said channels being approximately vertical and opposed to each other at the curved portion 37 (Fig. 4) to permit the easy curving of the layers 12 and 13 and gradually approaching horizontal and becoming frontwardly opening at the receiving 30 end portion 38 (Figs. 1 and 5) to permit the easy insertion of the layers, as the layers 12 and 13 are more easily insertible if nearly parallel to each other. Said channels 40 and 41 are connected at the receiving end portion 38 by a rearwardly closed channel shaped yoke portion 43 receiving the outer edge 14 of the edging and being cut away, as at 44 at the curving portion 37 to permit 45 puckering of the edging thus to prevent the choking of channel shaped yoke portion.

A body fabric supporting plate 45 secured to the top face of said upper member 32 of the lower binder element 30 extends laterally away from the binder elements for supporting the main body fabric 10.

The operation of the device is simple and obvious. The binder is attached relative to the foot, as shown; the edging started 50 in as shown by the dotted lines in Fig. 1, with the inner edges 15 and 16 in the channels 40 and 41 and the overseamed edge 14 in the channel yoke 43. The edging is then pushed in until the layers 12 and 13 dispose 55 themselves in the binder elements 20 and 31, as indicated in Fig. 3. The foot 17 is then raised to permit the easy insertion of the body fabric 10 between the layers 12 and 13, after which the foot is lowered and the 60 stitching operation commenced. The stitch-

ing continues until a line of stitches 46 (Fig. 6) secures the edging to the body fabric.

I claim:

1. A binder for use with sewing machines 70 for attaching superposed layers to a fabric, said binder comprising separate binder elements for guiding the separate layers and provided with means for separating the layers, one of said elements being fixed and 75 the other secured to the machine foot and movable therewith relative to the other element.

2. In combination, upper and lower binder elements; superposed opposed guide channels 80 for discharging into said elements and provided with a curved portion curving rearwardly and laterally toward the receiving end; and a forwardly opening channel shaped yoke portion joining said guide channels 85 at the receiving end and terminating short of the curved portion; said guide channels being approximately vertical and opposed to each other at the curved portion and gradually approaching horizontal away 90 from said curved portion.

3. In combination, upper and lower binder elements; superposed opposed guide channels for discharging into said elements and provided with a curved portion curving 95 rearwardly and laterally toward the receiving end; and a forwardly opening channel shaped yoke portion joining said guide channels at the receiving end and terminating short of the curved portion. 100

4. A binder for attaching to body fabrics edging comprising upper and lower layers secured together by overseaming at the outer edge; said binder comprising in combination, with the presser foot of a sewing machine, 105 a bracket plate provided with an end guide face; an upper inwardly laterally opening channel shaped binder element receiving the inner edge of said upper layer and formed with a lower member, an upper member 110 secured to the presser foot and having its edge disposed close to said face; a lower channel shaped sheet-metal binder element open at the inner side and receiving the inner edge of the lower layer and disposed under 115 the upper element and formed with an upper member, a lower member secured to said face, and a rearwardly and inwardly curved guide formed with lower and upper guide channels for guiding said layers into said 120 upper and lower elements respectively; said channels being connected at their receiving end portions by a rearwardly closed channel shaped yoke portion receiving the outer edge of the edging, and being cut away at 125 the curving portion to permit the puckering of the edging.

5. A binder for use with sewing machines for attaching, to the edge of body fabrics, edging comprising upper and lower layers 130

joined together at the outer edge and having inner edges; said binder comprising a sheet-metal channel shaped upper binder element longitudinal to the path of feed and receiving the inner edge of said upper layer and closed at the outer side and formed with a narrow lower member downwardly inclined toward its edge with an inclination grad-

ually steeper at the front end, a wide upper member having its edge downwardly inclined; said outer edge being split at the forward end and the forward ends of said members diverged; and a lower binder element for guiding the lower layer. 10

BERNARD M. KRELL.
